UNITED STATES PATENT OFFICE.

GEORGE WORDINGHAM, OF MILWAUKEE, WISCONSIN.

LAUNDRY-ENVELOP.

1,105,120.

Specification of Letters Patent.

Patented July 28, 1914.

Application filed December 17, 1912. Serial No. 737,298.

To all whom it may concern:

Be it known that I, GEORGE WORDINGHAM, citizen of the United States, residing at Milwaukee, in the county of Milwaukee and 5 State of Wisconsin, have invented certain new and useful Improvements in Laundry-Envelops, of which the following is a specification.

This invention relates to laundry envelops, 10 or more specifically to an envelop or wrapper designed to receive handkerchiefs, small articles of table linen, napkins, and the like, after they have been laundried, the object of the invention being to protect the laundried 15 article from becoming soiled prior to delivery to the owner.

Another aim of the invention is to so construct the envelop or wrapper that it may accommodate one or any reasonable number 20 of laundried articles, and will hold these articles firmly in place and in flat condition.

Another aim of the invention is to provide an envelop or wrapper so constructed and arranged that the articles contained therein 25 may be inspected without the necessity of removing them therefrom.

A still further object of the invention is to provide a wrapper or envelop of the type mentioned which, at the time of its sealing, 30 may be caused to securely bind the articles disposed ther within regardless of the thickness of the contents.

For a full understanding of the invention reference is to be had to the following description and accompanying drawing, in 35 which:—

Figure 1 is a perspective view of the laundry envelop or wrapper embodying the present invention. Figs. 2, 3 and 4 are edge- 40 views of the wrapper illustrating the manner in which it may be arranged to accommodate laundried articles varying in thickness or number. Fig. 5 is a perspective view of the wrapper in open condition.

45 Corresponding and like parts are referred to in the following description and indicated in all the views of the drawings by the same reference characters.

In the drawings the envelop or wrapper 50 is illustrated as consisting of a back and a front, the back being indicated by the numeral 1 and the front by the numeral 2. The back 1 is of relatively stiff material, preferably cardboard, whereas the front 2 is of 55 relatively thin and flexible material such as

onion skin paper which is ordinarily transparent or translucent. In connecting the back and front, the front 2 is attached at one edge portion to the under side of the back 1 by a strip of adhesive 3 and in this condition the envelop or wrapper is placed upon the market, the opposite end of the front being left unattached to the back 1. By referring to the several figures of the drawing it will be seen that the front 2 is of a width considerably greater than the back 1.

Inasmuch as handkerchiefs and other similar articles, when laundried, are folded to substantially square form, the back 1 is preferably square and of such dimensions as 70 to conform to the width of the folded article which is to be disposed within the wrapper. On the other hand, the front 2, being of greater width than the back 1, is substantially oblong in form. The narrow strip 4, 75 of adhesive, is applied upon the under side of the back 1 at that edge opposite the edge to which the front 2 is initially and permanently attached, and it will be understood that after the laundried article has been disposed upon the back 1, the front 2 may be laid over the same and drawn tightly around that edge of the back at which the strip 4 is located, the strip having been previously moistened. The underlying portion of the 80 front is then pressed against the under face of the back 1 and will be secured thereto by the adhesive 4.

By referring to Figs. 2, 3 and 4 of the drawings it will be apparent that any reasonable number of folded laundried articles of the proper size may be arranged within the wrapper and protected thereby, and it will further be apparent that due to the fact that the front is thin and flexible and may be 90 drawn tightly over the articles disposed against the back 1 the articles will be securely held against loss, although the 95 wrapper is open at its top and bottom.

If desired, the representation of a tied ribbon may be printed upon the front 2, as indicated at 5, so as to give to the wrapper the appearance of a tied package.

Having thus described the invention what is claimed as new is:—

A wrapper for laundried articles consisting of a relatively stiff back having a narrow zone of adhesive applied to its obverse side at each lateral edge thereof, the said lateral edges being parallel, and a relatively 110

thin flexible front initially and permanently secured at one edge to the obverse side of the back through the medium of one of the said zones of adhesive, the said front being of a width considerably greater than the width of the back and being adapted to have a greater or less area of its surplus width folded to lie beneath the back and to be secured thereto

through the medium of the other zone of adhesive.

In testimony whereof I affix my signature in presence of two witnesses.

GEORGE WORDINGHAM. [L. s.]
